UNITED STATES PATENT OFFICE.

CHARLES E. CONNER, OF AUBURN, MAINE, ASSIGNOR TO UNITED SHOE MACHINERY CORPORATION, OF PATERSON, NEW JERSEY, A CORPORATION OF NEW JERSEY.

ATTACHING MACHINE.

Application filed November 26, 1920. Serial No. 426,489.

To all whom it may concern:

Be it known that I, CHARLES E. CONNER, a citizen of the United States, residing at Auburn, in the county of Androscoggin and 5 State of Maine, have invented certain Improvements in Attaching Machines, of which the following description, in connection with the accompanying drawings, is a specification, like reference characters on 10 the drawings indicating like parts in the several figures.

My invention relates to attaching machines, especially involving the jacks or work-supports found in such apparatus as 15 that employed for nailing or tacking counters to the soles of turn shoes prior to their turning. There is a machine of this character which is a modification of the well-known Lightning heeler, and is described in 20 an application filed in the name of Joseph H. Pope on October 4, 1920, Serial No. 414,501. To support the counter in position for nailing, the die-block of the machine is provided upon its under side with a 25 counter-supporting block, against which the heel-seat of the shoe operated upon is pressed during the nailing of the counter. In attaching high counters, the travel of the cross-head carrying the jack may not be 30 sufficient to remove the upper edge of the counter below the supporting block, and this interferes with the drawing out of the jack to remove the work.

An object of this invention is to provide 35 a machine which operates in this manner upon the work, but without interference between the attached element and its support, and without requiring the operator to perform special acts to attain the desired result. To this end, I combine with a work-support, or jack, and mechanism for operating upon the work, as nailing instrumentalities, means for temporarily retaining the work-support in position for the operation, 40 together with means for actuating the retaining means to release the work-support, and means controlled in the operation of the machine and independently of movement of the work-support for restoring said work-support to operating position. This automatic control under the power of the machine may be in the nature of a preparation of the restoring means for operation, as by effecting the compression of a spring, which 45 thereafter causes the work-support to be re-

turned to the operating position. To allow the restoration to take place at the desired time, there is associated with the restoring means, a means for holding it as thus prepared. The holding means, as illustrated, 60 consists of a latch cooperating with the spring, and it may be caused to act as a result of movement of the work-support. By making this incident to another operation, the operator is not only relieved of the 65 effort of preparing the restoring means for action in the manner already pointed out, but also of the initiation of the restoring action. The retaining means for the work-support, which limits its movement or holds 70 it for the attaching operation, is shown as movable to allow the support to be freed to retreat from the attaching mechanism, and this movement is preferably controlled in the operation of the machine. The use of 75 this organization in a counter-attaching machine results in the jacked work with the attached counter being held against movement for the attaching operation, released 80 and moved away from the attaching mechanism so that it may be shifted without contact between the counter and its support, and finally the jack restored to and retained 85 in the attaching position, all without effort on the part of the operator other than what has been heretofore required in connection with the ordinary operation of machines of the same character.

The accompanying drawing illustrates my invention in connection with a counter-attaching machine,

Fig. 1 being a front elevation, partly in section, of such an apparatus;

Fig. 2, an enlarged front elevation, with parts broken away, of the jack-post and more closely associated controlling elements; and

Fig. 3, an enlarged side elevation of the jack.

The general organization of the machine I have chosen to illustrate may be similar to the previously mentioned Lightning heeler. Of this it will be sufficient to say that it has a frame 10, carrying above the usual actuating mechanisms a die-block 12, with the nail-receiving openings of which co-operate drivers 14. These drivers are fixed to a top girt 15 carried by reciprocating side rods 16 and 18. A jack J, arranged to receive a last L, upon which is to be support- 110

ed a shoe S which is to have attached to it a counter C, is mounted upon the customary reciprocatory cross-head 20. Beneath and having openings in alinement with the die-block openings is secured a counter-support, conveniently furnished by a block 22. At the rear of the die-block is mounted a back-gage 24, which, by its contact with the work upon the jack, acts to position this in 10 correct relation to the support 22.

The jack J includes a base or support 26, mounted to slide in horizontal ways 28 in the cross-head from the front toward the rear of the machine. This lateral movement carries the jacked work into the attaching position beneath the support 22, or outwardly therefrom free from the die-block to enable the operator to apply to the jack the lasted work, or to remove this with 15 the attached counter. At the rear of the base, rising vertically from it, is a tubular standard 30, in which is arranged to move a jack-post 32 having at its upper extremity a spindle 34 to enter the opening in the cone 20 of the last L. Situated beneath the toe of the last, I have shown a toe-rest 36, which may be of any suitable form, supported upon an arm 38 extending from the jack-post and being adjustable vertically and 25 horizontally to bring it into correct relation with the toe of the lasted shoe supported upon the jack. The jack-post is threaded at 30 40, and on this threaded portion is a contact member, provided by a nut 42. With 35 the under side of this nut may contact a retaining member, consisting of a slide 44 carried for horizontal movement at the top of a lateral extension 43 of the base 26. Upon the lower side of the slide is formed 40 or secured a rack 46, having meshing with it a pinion 48, the spindle of which is journaled in the extension 43. With this pinion also meshes a gear-segment 50, journaled 45 upon the standard extension and having projecting from it in a substantially horizontal direction an arm 52. Between this arm and the jack base extends a helical tension-spring 54, which acts through the gearing connections to urge the slide 44 normally 50 toward the jack-post. Fixed upon the side 55 rod 16, adjacent to the jack, is a bracket 56, having pivoted at the inner side of the rod a contact member 58, which is held by a spring 60 toward the jack and with its end 60 in vertical alinement with the extremity of the arm 52. When, in the operation of the machine, the side rod descends, the member 58 moves idly by the arm, yielding outwardly to avoid interference. On the return 65 or upward movement, however, the contact member, striking the arm, rotates the gear-segment in a clockwise direction, this movement being transmitted through the pinion to the slide, carrying this away from the jack-post, so that it is removed from beneath

the nut 42. The jack thus freed may fall by gravity until the nut contacts with the top of the standard 30.

Interposed between the jack-post and the standard is a sleeve 62, fitting said standard for reciprocation within it, and in which the jack-post has a sliding fit. Between the base and the sleeve is situated such a motor means as a helical compression spring 64, of such length and strength that it will raise 70 the jack and work until the nut 42 is above the top of the slide 44. The upward movement of the sleeve within the standard may be limited by the reduced end of a screw 66 threaded through the wall of the standard into a vertical slot of suitable length in the sleeve. A similar screw 68, threaded through the sleeve, may project into a slot in the jack-post to prevent its rotation. From one side of the sleeve 62 is a projection 70, passing through a vertical slot in the standard and lying in the path of a contact arm 72 secured upon the side rod 18 of the machine. When the top-girt is lowered in its driving stroke, the member 72, striking the projection 70, depresses the sleeve 62 and compresses the spring 64. In this lowered position, the sleeve is held against the expansive force of the spring by a latch 74, pivoted at 76 upon the jack base and having an engaging end entering a depression 78 in the sleeve. The latch is forced normally toward the sleeve by a spring 80 interposed between it and the base, and the latch may be withdrawn from the sleeve opening to release the sleeve by contact of its lower extremity with a bar 82 fixed upon or forming a part of the frame at the front of the cross-head 20. This contact and the disengagement of the sleeve by the latch occur when the jack is drawn out for the purpose of removing from it the shoe with its attached counter.

In using a counter-attaching machine arranged in accordance with the present invention, the operator applies to the block 22 the counter C which is to be attached, and, the jack base 26 being drawn forward, places the lasted shoe S upon the pin 34 of the jack. The applied counter, it will be assumed for the purposes of the present description, is of a greater height when attached to the shoe than the downward travel of the cross-head 20. That is, when the cross-head is lowered after the attachment of the counter, the upper edge of said counter will still project above the bottom of the block 22. The jack is then pushed in until the rear of the shoe contacts with the gage 24. The work thus positioned, the operator starts the machine, the cross-head rising to clamp the heel-seat of the shoe against the counter upon its block, and the drivers descending force through the counter into the heel-seat of the shoe the 130

nails or tacks which have previously been supplied by the usual loading mechanism to the openings in the die-block. During this movement of the drivers, involving the descent of the side rods, the contact member 72 strikes the projection 70, lowering the sleeve 62, which is locked by the latch 74, the spring 64 being held compressed. The jack remains supported by the contact of 5 the nut 42 with the slide 44, which at this time is held at its inward position by the spring 54. As the top girt rises after the driving operation, the contact member 58, after having traveled downwardly past the 10 arm 52 without action, raises the arm and through the associated gearing moves the slide 44 away from the jack-post. This carries it from beneath the nut 42, and the jack, being thus freed, falls by gravity to its lowest position, at which time the nut 15 42 is in proximity to the top of the standard 30. The upper extremity of the now depressed and locked sleeve 62 is also, it should be noted, at or below the top of the standard, so that it does not interfere with the descent of the jack. This fall of the 20 jack lowers it and the shoe sufficiently to carry the upper edge of the attached counter below the bottom of the block 22, so that said counter is free to move past the block. The jack is then drawn out, and the lasted shoe is taken from the post. At the end of the forward travel of the jack, the tail of the latch 74 comes in contact 25 with the bar 82, drawing the engaging end of the latch out of the opening 78. The sleeve 62 is thereby freed, and the spring 64 expanding, raises the sleeve, which, by its contact with the nut 42, also elevates 30 the jack. This action continues, the side of the nut moving along the inner face of the slide until the lower face of the nut is above the upper edge of said slide, when the spring 54, acting through the arm 52 35 and associated gearing, carries the slide beneath the nut. The elements of the jack are now restored to their initial condition, and are ready to receive another lasted shoe. This having been applied, the jack 40 is again pushed in beneath the block 22, and, with the application of a counter to this block, the machine is ready for the succeeding operation.

Having described my invention, what I claim as new and desire to secure by Letters Patent of the United States is:

1. In a machine of the class described, mechanism for operating upon the work, a movable work-support, means for temporarily retaining the work-support in operating position, means for actuating the retaining means to release the work-support, and means for restoring said work-support to the operating position, said restoring 50 means being controlled in the operation of

the machine and independently of movement of the work-support.

2. In a machine of the class described, mechanism for operating upon the work, a movable work-support, means for temporarily retaining the work-support in operating position, means for actuating the retaining means to release the work-support and leave it free to be moved by gravity from the operating position, means for restoring the work-support to the operating position, means for preparing the restoring means for operation, and means for temporarily holding the restoring means as thus prepared. 70

3. In a machine of the class described, mechanism for operating upon the work, a movable work-support, means for temporarily retaining the work-support in operating position, means for actuating the retaining means to release the work-support, means for restoring the work-support to the operating position, means for preparing the restoring means for operation, means for temporarily holding the restoring means as thus prepared, and means effective in the movement of the work-support for releasing the holding means. 80

4. In a machine of the class described, mechanism for operating upon the work, a work-support movable toward and from the operating mechanism and laterally with respect thereto, means for temporarily retaining the work-support in operating position, means for actuating the retaining means to release the work-support, means for restoring the work-support to the operating position, means for preparing the restoring means for operation, means for temporarily holding the restoring means as thus prepared, and means effective in the lateral movement of the work-support for releasing the holding means. 95

5. In a machine of the class described, mechanism for operating upon the work, a movable work-support, means for temporarily retaining the work-support in operating position, means for actuating the retaining means to release the work-support, a spring acting as the sole force in the restoration of the work-support to the operating position, and means acting in the operation of the machine for compressing the spring. 110

6. In a machine of the class described, mechanism for operating upon the work, a movable work-support, means for temporarily retaining the work-support in operating position, means for actuating the retaining means to release the work-support, a spring for restoring the work-support to the operating position, means acting in the operation of the machine for compressing the spring, a latch for the spring, and 120

means arranged to actuate the latch in the movement of the work-support.

7. In a machine of the class described, mechanism for operating upon the work, a movable work-support, means for temporarily retaining the work-support in operating position, means controlled in the operation of the machine for actuating the retaining means to release the work-support, 10 and means moved by the machine and while disengaged from the work-support for thereafter restoring said work-support to the operating position.

8. In a machine of the class described, reciprocal mechanism for operating upon the work, a movable work-support, means for temporarily retaining the work-support in operating position, means controlled in the movement of the operating mechanism 20 in one direction for actuating the retaining means to release the work-support, and means for restoring the work-support to the operating position, there being control exercised over the restoring means in the movement of the operating mechanism in the opposite direction.

9. In a counter-attaching machine, movable nailing mechanism, a counter-supporting member co-operating with the nailing 30 mechanism, a work-support movable toward and from said counter-supporting member, movable means for limiting the movement of the work-support from the counter-supporting member, and power-operated means 35 for moving the limiting means.

10. In a counter-attaching machine, movable nailing mechanism, a counter-supporting member co-operating with the nailing mechanism, a work-support movable toward 40 and from said counter-supporting member, movable means for limiting the movement of the work-support from the counter-supporting member, and means movable with the nailing mechanism for moving the limiting means out of co-operation with the work-support.

11. In a counter-attaching machine, movable nailing mechanism, a counter-supporting member co-operating with the nailing mechanism, a work-support movable toward and from said counter-supporting member, movable means for limiting the movement of the work-support from the counter-supporting member, and motor means for carrying the work-support into co-operation with the limiting means.

12. In a counter-attaching machine, movable nailing mechanism, a counter-supporting member co-operating with the nailing mechanism, a work-support movable into and out of alinement with the counter-supporting member and toward and from said counter-supporting member, movable means for limiting the movement of the work-support from the counter-supporting mem-

ber, motor means for carrying the work-support into co-operation with the limiting means, and power-operated means for preparing the motor means for action.

13. In a counter-attaching machine, movable nailing mechanism, a counter-supporting member co-operating with the nailing mechanism, a work-support movable into and out of alinement with the counter-supporting member and toward and from said counter-supporting member, movable means for limiting the movement of the work-support from the counter-supporting member, a spring acting upon the work-support to carry it into co-operation with the limiting means, and means movable with the nailing mechanism for compressing the spring.

14. In a counter-attaching machine, movable nailing mechanism, a counter-supporting member co-operating with the nailing mechanism, a work-support movable into and out of alinement with the counter-supporting member and toward and from said counter-supporting member, movable means for limiting the movement of the work-support from the counter-supporting member, a spring acting upon the work-support to carry it into co-operation with the limiting means, means movable with the nailing mechanism for compressing the spring, and a latch for the spring arranged for operation in the movement of the work-support out of alinement with the counter-supporting member.

15. In a counter-attaching machine, movable nailing mechanism, a counter-supporting member co-operating with the nailing mechanism, a work-support movable into and out of alinement with the counter-supporting member and toward and from said counter-supporting member, movable means for limiting the movement of the work-support from the counter-supporting member, motor means for carrying the work-support into co-operation with the limiting means, power-operated means for moving the limiting means, and power-operated means for preparing the motor means for action.

16. In an attaching machine, movable attaching mechanism, a base, a jack mounted for movement upon the base toward and from the attaching mechanism, a slide movable upon the base into and out of the path of a surface upon the jack, connections for moving the slide, and a contact member movable with the attaching mechanism for engagement with the slide connections.

17. In an attaching machine, movable attaching mechanism, a base, a jack mounted for movement upon the base toward and from the attaching mechanism, a movement-limiting member movable upon the base into and out of the path of a surface of the

jack, gearing for actuating the limiting member, and a contact member movable with the attaching mechanism and acting upon the gearing.

5 18. In an attaching machine, movable attaching mechanism, a base, a jack mounted upon the base, a spring exerting its force to move the jack toward the attaching mechanism, a member interposed between 10 the spring and jack, a contact member movable with the attaching mechanism for engagement with the interposed member, and retaining means for the interposed member.

15 19. In an attaching machine, movable attaching mechanism, a base, a jack-post movable in the base, a sleeve surrounding the jack-post, a spring acting upon the sleeve, a contact member movable with the attaching mechanism and co-operating with the 20 sleeve, and a latch mounted upon the base for engagement with the sleeve.

25 20. In an attaching machine, movable attaching mechanism, a base movable with reference to the attaching mechanism, a jack mounted for movement upon the base, a spring exerting its force to move the jack toward the attaching member, a member interposed between the spring and jack, a contact member movable with the attaching 30 mechanism for engagement with the interposed member, holding means for the interposed member, and means arranged to release the holding means in the movement of the base.

35 21. In an attaching machine, movable attaching mechanism, a base movable with reference to the attaching mechanism, a jack-post movable in the base, a sleeve surrounding the jack-post, a spring acting upon

the sleeve, a contact member movable with 40 the attaching mechanism and co-operating with the sleeve, a latch mounted upon the base for engagement with the interposed member, and a member with which the latch contacts to release the interposed member. 45

22. In an attaching machine, movable attaching mechanism, a base, a jack mounted for movement upon the base toward and from the attaching mechanism, a slide movable upon the base into and out of the path 50 of a surface upon the jack, connections for moving the slide, a spring exerting its force to move the jack toward the attaching mechanism, a member interposed between the spring and jack, holding means for the 55 interposed member, and means movable with the attaching mechanism for co-operation with the slide connections and with the interposed member.

20. In an attaching machine, movable attaching mechanism, a base movable with reference to the attaching mechanism, a jack mounted for movement upon the base, a slide movable upon the base into and out of the path 60 of a surface upon the jack, connections for moving the slide, a spring exerting its force to move the jack toward the attaching mechanism, a member interposed between the spring and jack, means movable 65 with the attaching mechanism for engagement with the slide connections and with the interposed member, holding means for the interposed member, and means arranged for the interposed member, and means arranged to actuate the holding means in the 70 movement of the base. 75

In testimony whereof I have signed my name to this specification.

CHARLES E. CONNER.
